[57] CLAIM

The ornamental design for a bicycle lock mounting bracket, as shown and described.

DESCRIPTION

FIG. 1 is a top, front and right side perspective view of a bicycle lock mounting bracket showing my new design with connecting bicycle handlebars and lock shown in phantom lines;

FIG. 2 is a front elevational view thereof;

FIG. 3 is a bottom plan view thereof;

FIG. 4 is a rear elevational view thereof; and,

FIG. 5 is a right side elevational view thereof, the left side being a mirror image of the right side.
